UNITED STATES PATENT OFFICE.

SIMON BRAUNSTEIN, OF BROOKLYN, NEW YORK.

DESIGN FOR A KNITTED BLOUSE.

Application filed February 26, 1927. Serial No. 20,911. Term of patent 3½ years.

To all whom it may concern:

Be it known that I, SIMON BRAUNSTEIN, a citizen of the United States, residing in Brooklyn, county of Kings, and State of New York, have invented a new, original, and ornamental Design for Knitted Blouses, of which the following is a specification, reference being had to the accompanying drawing, forming a part thereof.

The drawing is a front view of a knitted blouse showing my new design.

I claim:

The ornamental design for a knitted blouse substantially as shown.

Signed at Brooklyn, N. Y., this 23 day of February, 1927.

SIMON BRAUNSTEIN.
